FLUORINATED ETHERS AND DERIVATIVES
 Harvey A. Brown, East Oakdale Township, Washington County, and Robert J. Koshar, Lincoln Township, Washington County, Minn., assignors to Minnesota Mining and Manufacturing Company, St. Paul, Minn., a corporation of Delaware
 No Drawing. Filed Feb. 2, 1959, Ser. No. 790,334
 11 Claims. (Cl. 8—116.2)

This invention relates to halomethylethers and more particularly to certain new N-perfluoroalkylsulfonamidoalkyl halomethylethers and quaternized derivatives thereof, and to a process for rendering textiles soil-resistant as well as oil and water repellent.

The novel halomethylethers of the invention contain a halogen atom attached to a perfluoroalkylsulfonamidoalkyl group through a labile oxyethylene radical. These halomethylethers are found to react with tertiary organic bases to form quaternary ammonium derivatives. When the perfluoroalkyl group contains from about 6 to about 12 fully fluorinated carbon atoms, it has been found that these compounds can be employed as textile finishes, and particularly to treat cellulosic materials such as cotton to produce a chemically bonded water and oil repellent finish material for such cellulosic materials.

While it has heretofore been found possible to produce valuable and useful soil resistance, and oil and water repellency, in wool and certain synthetic fibers, it has been difficult to produce lasting effects on the cellulosic fibers. The finishes heretofore developed for this purpose, such as those which employ amido-quaternary amines as described in U.S. Patent 2,303,191, have been relatively easily removed, often by a single laundering operation. They have also required the deposit of relatively large amounts of the treating agent on the fibers, as compared with the compositions of the present invention.

It is an object of this invention to provide quaternizable halomethyl ethers possessing fluorocarbon "tails."

Another object of this invention is to provide agents by means of which cellulosic materials and particularly cotton fibers can be rendered lastingly oil and water repellent. A further object of this invention is to provide oil and water repellent cellulosic materials such as cotton cloth. Still another object of the invention is to provide a process for rendering cellulosic materials soil-resistant. Other objects will become apparent hereinafter.

In accordance with the above and other objects of this invention certain novel halomethyl ethers have been discovered which are useful for the production of quaternary salts containing a fluorocarbon "tail." These compounds can be represented by the formula:

wherein R_f is a perfluoroalkyl group containing 4 to 12 carbon atoms (providing the fluorocarbon "tail" which has certain useful characteristics as set forth in U.S. Patent 2,803,656, R is an alkylene bridging group containing 1 to 12 carbon atoms, R' is hydrogen or an alkyl group containing 1 to 6 carbon atoms and X is chlorine or bromine.

It has been found that these novel halomethyl ethers readily react with tertiary organic bases to produce novel surface-active quaternary salts represented by the formula:

wherein Q represents a nitrogenous organic residue having the free valence attached to the nitrogen atom and three

other valences attached to at least two carbon atoms, and bearing a positive charge.

It has further been found that the quaternary salt derivatives of the compounds of the invention can be applied to woven and non-woven fabrics as more fully described hereinafter to provide oil and water repellency with improved resistance to laundering. For this purpose those quaternary compounds represented by the formula:

wherein X is chlorine or bromine, R_f is a perfluoroalkyl group containing from 6 to 12 carbon atoms and n is an integer from about 4 to 13, are particularly preferred, as giving especially useful results, notably with regard to launderability. It will be noted that "Q" in the above general formula is

in this instance.

Broadly speaking, the halomethyl ethers of the invention are prepared by reaction of perfluoroalkanesulfonamidoalkanols of the general formula:

wherein R_f , R and R' have the significance set forth above, and which are described and claimed in U.S. Patent No. 2,803,656, with formaldehyde and anhydrous hydrogen chloride or anhydrous hydrogen bromide. The resulting perfluoroalkanesulfonamidoalkyl halomethyl ethers are waxy solids having softening points of from about 25° to about 100° C.; that is, they vary in consistency from that of hard butter to that of beeswax or carnauba wax. When sufficiently pure they are white, but as commonly obtained they are slightly yellowish in color. This does not affect their utility for quaternization, and special purification prior to quaternization is not necessary.

The process for preparation of the halomethyl ethers is conveniently carried out by passing the selected anhydrous hydrogen halide in gaseous form into a solution of the alkanol and paraformaldehyde in an inert solvent such as toluene, benzene and the like, until there is substantially no further absorption of the hydrogen halide. As the reaction is not strongly exothermic, no temperature control is required, although heating from about 25° C. to 100° C. (depending to an extent on the boiling point of the solvent used) may be resorted to to insure completion of the reaction. The halomethyl ethers are then readily isolated by evaporation of the solvent and are obtained as residues which can be purified if desired as by fractional distillation under reduced pressure, recrystallization or the like, but which are conveniently employed without further purification, e.g. for quaternization. Although amide linkages are sometimes cleaved by acidic reagents, this does not appear to occur during the preparation of the compounds of this invention even though the strongly hydrogen halides are employed.

Quaternization is conveniently effected by dissolving the selected halomethyl compound in anhydrous ether or other solvent (such as toluene, benzene or dioxane) in which the quaternary salt is insoluble and adding the desired tertiary organic base, while heating at a temperature in the range of about 25° C. to 100° C. For this purpose tertiary amines, including trialkyl amines such as trimethylamine, tributylamine and tridodecylamine; alkylamines such as dimethylaniline; and heterocyclic amines such as pyridine, picoline, lutidine, quinoline and

the like are suitable. Pyridine is particularly preferred for convenience and economy in the formation of cloth-treating agents as shown above.

The quaternary derivatives of the compounds of the invention are employed for treating woven or non-woven fibrous materials including wool, cotton, rayon, acetate, nylon and the like textiles, or paper, leather, wood, felt and similar organic fibrous constructions, and particularly cellulosic materials, by applying the selected quaternary derivatives, in aqueous medium buffered to about pH 6, to the cloth, removing any excess, drying at a temperature in the range of about 40° to 100° C., and heating the dried material to about 100° to 140° C. for a period of the order of about 5 to 30 minutes to fix the finish. Thereafter the material is desirably treated with a mildly alkaline washing to remove any residual acidic material, and dried. The treatment may be followed by a simple aqueous wash before drying, if desired, although this may be omitted since subsequent laundering of the treated fabric accomplishes the same purpose. The treatment may be termed a finishing treatment, since it is most usefully applied after weaving, forming, dyeing, weighting, filling or the like have been carried out. The cloth so treated appears to contain residual combined fluorine, indicating that at least a portion of the treating agent has reacted in some fashion, probably through the hydroxyl groups present in the fiber, although this theory is not to be construed as limiting the invention.

It is a surprising feature of cotton fabric treated with these quaternary derivatives that not only is the cloth rendered oil and water repellent but also it possesses a considerable degree of soil resistance, that is it does not become soiled as readily as untreated fabric. Furthermore, when soiled the fabrics thus treated are readily launderable to a clean state, after which they retain their oil and water repellency. The value of cloth so treated, for example, for children's clothes, or for uniforms for workers around oily machinery, automotive service men and the like will be readily apparent.

The color of the fabrics treated with the compositions of the invention, and their tensile strength, are not affected by the treatment. The hand of cotton fabrics appears to be improved by the treatment.

It is noted that the finishing treatment of the invention can be applied to resin-treated, wrinkle-resistant fabrics without adversely affecting the desirable non-wrinkling feature of such fabrics.

The compositions have furthermore been found to confer oil and water-repellency on vitreous surfaces and the like, such as glass, including glass fibers.

The procedure for the preparation of the halomethyl ethers of the invention, their conversion to quaternary compounds, and the application of the latter to fabrics, especially cellulosic materials, are more specifically illustrated in the following examples, in which all parts are by weight and all percentages w/v. unless otherwise specified.

EXAMPLE 1

Anhydrous hydrogen chloride is passed through a solution of 155 parts of N-methyl-perfluoroctanesulfonamido-hendecanol (prepared as described in Example 6 of U.S. Patent 2,803,656) in 320 parts of toluene containing 6.9 parts of paraformaldehyde, until no further absorption occurs and the reaction is complete. The solution is evaporated under reduced pressure to remove toluene leaving the chloromethyl ether as a residue. N-methyl-11-perfluoroctanesulfonamido-hendecanoxymethyl chloride is a hard waxy solid which melts at about 50° C. The corresponding pyridinium salt is prepared therefrom by dissolving the above chloromethyl ether in about 300 parts of ether, adding 17.9 parts of pyridine and refluxing the solution for 1 hour. A precipitate of the quaternary salt forms and is collected, washed with ether and dried. N-methyl-11-(perfluoroctanesulfonamido)hendecanoxy -

methyl pyridinium chloride thus prepared melts at about 93-108° C.

Analysis.—Calculated for $C_{26}H_{32}F_{17}N_2O_3SCl$: 3.45 percent N. Found: 3.47 percent N.

EXAMPLE 2

The process for production of soil-resistant, water and oil-repellent cloth using the quaternary derivatives of the compounds of this invention is carried out as follows:

- 10 The treating solution is prepared by warming sodium acetate trihydrate and the selected treating agent in water at the desired concentrations, which can range from about 0.1 to about 5 percent, at about 30° to 40° C. until solution is effected. It is to be noted that at higher concentration the solution tends to become mucilaginous and difficult to handle, resembling a colloidal dispersion. The cloth to be treated is soaked in the solution for 1 minute, removed and squeezed so that a weight of solution approximately equal to 75 to 125 percent of the weight of the cloth is retained. Under these conditions, the preferred concentration of treating solution ranges from about 0.5 to about 2 percent. The cloth is then dried for about 10 to 30 minutes at 40° to 100° C. and the treatment is fixed by heating the cloth for about 5 to 30 minutes at from about 100° to 140° C. The fixed, treated cloth is washed for about 30 minutes in an aqueous solution containing 0.1 percent w/v. of sodium lauryl sulfate and 0.2 percent w/v. sodium carbonate, at about 50° to 60° C., rinsed thoroughly and again dried. Other alkaline agents, such as dilute alkali metal hydroxides, bicarbonates, ammonium hydroxide and the like can be used instead of alkali metal carbonates.

The effectiveness of the treatments is determined by means of tests for spray rating, oil repellency rating and visual estimation of soil repellency both before further treatment and after one or more cycles of laundering.

For test purposes, laundering is accomplished by washing in a 1957 model automatic washing machine of the stationary tub type using a detergent under normal household procedures or by means of a standard 60 minute cycle in a Launder-O-Meter, using chip soap as specified in ASTM D-496.

Determination of water repellency rating is by means of the "Spray Test" (Standard Test Method No. 22-52, published in the 1952 Technical Manual and Yearbook of the American Association of Textile Chemists and Colorists, vol. XXVIII, p. 136).

Oil repellency of the treated cloth is measured by a severe test in which its resistance to penetration by solutions of mineral oil in heptane is determined. (Higher proportions of heptane bring about quicker penetration.) A material wet by mineral oil alone in less than 3 minutes rates zero, if it is only wet after 3 minutes it rates fifty, while resistance to penetration by a mixture of equal volumes of heptane and mineral oil rates 100. The ratings for resistance for 3 minutes are as follows.

Percent heptane:	Rating
60 0	50
20	70
30	80
40	90
50	100
60	100+

A rating of 70 or higher indicates a high degree of resistance to staining by salad oil and the like.

The N-methyl-perfluoroctanesulfonamido-hendecanoxymethyl pyridinium chloride of Example 1 is applied to kier-boiled standard cotton jeans cloth in 1.5 percent, 2.0 percent and 2.5 percent w/v. solutions containing 1 percent of sodium acetate trihydrate as described hereinabove, drying at about 100° C. for about 30 minutes, followed by curing at 135° C. for 5 minutes.

After washing as described above, rinsing and again

drying, it is subjected to tests to determine oil and water repellency with the following results:

Table I

Cone. of treating solution	Spray rating	Oil repellency	Percent F in fabric
1.5 percent	80	100	(¹)
2.0 percent	80+	100	0.39
2.5 percent	70	100+	1.3

¹ Not determined.

A further sample using the same fabric is prepared using a 2.5 percent solution of the treating agent containing 0.4 percent sodium acetate, treating the cloth as set forth above. It is home-laundered repeatedly in softened water, using as a detergent polyglycol-ether stearate (available commercially under the trademark name "All"), then tested for oil and water repellency. The results are found to be:

Table II

	Spray rating	Oil repellency
Initial rating	80-	100+
After laundering:		
1x	80-	100+
2x	80-	100+
3x	70+	100+
4x	70+	100+
5x	70+	100
6x	70+	100
8x	70+	100
10x	70+	100

containing 1 percent of sodium acetate trihydrate by w./v. together with N-methyl-perfluorooctanesulfonamidoheptadecanoxymethyl pyridinium chloride in the concentrations indicated in Table III, and dried and cured under the conditions there set forth. After washing with a detergent (sodium lauryl sulfate), rinsing and drying, they are rated for oil and water repellency as well as dry soil resistance. Small portions of the fabric are removed and analyzed to determine the percentage of fluorine present.

10 Dry soil resistance simulates soil repellency of a material under especially exaggerated conditions. A control sample of untreated cloth and the treated sample to be tested are shaken together in a paper bag with about 2 ounces of a standard synthetic soil mixture having the 15 composition described in the report of Salisbury et al., American Dyestuff Reporter, March 26, 1956, p. 199, then removed and sharply struck against a solid object to remove loosely adherent soil and compared visually with a similarly soiled untreated sample. The ratings 20 are from 0 to 3. These correspond to visual estimation to

0—as dark as control (untreated cloth sample)

1—slightly less dark than control

2—more than about half as dark as control

3—less than about half as dark as control

25 While the ratings are subjective, and may vary to a certain extent as to the degree of soil involved, it is significant that there is markedly less soiling of samples treated with the compounds of the invention and this property is retained after laundering.

The conditions of treatment and results of tests after the initial rinsing and drying and after 3 launderings using the Launder-O-Meter are set forth in the following table.

Table III

Specimen No.	Percent T.A.	Dry temp., °C. ¹	Dry time, min.	Cure temp., °C.	Cure time, min.	Initial properties				Properties after 3 launderings			
						Oil	Spray	Dry soil	Percent F	Oil	Spray	Dry soil	Percent F
1	0.5	40	15	120	10	90	80	3	² 0.1	70	50	2	0.15
2	0.5	40	30	120	20	90	80	3	0.17	70	50	2	0.13
3	0.5	60	15	120	20	90	80	3	0.22	70	50	2	0.13
4	0.5	60	30	120	10	90	80-	3	0.24	70	50	1	0.12
5	1.0	50	22.5	105	15	100	80+	3	0.38	100	70	3	0.23

¹ Treating agent.

² Values low due to inhomogeneity of analytical samples.

³ Not determined.

The solution used for treating fabric as set forth above can also be applied to paper with slight modifications in procedure to avoid damaging the structure of the paper, which, as is well known, is weakened by treatment with water. Thus, the excess of treating solution is removed by permitting the paper to drip dry or by running the web between rolls, while drying and fixing are accomplished by heating the individual sheets or by hot-roll calendering long strips or continuous rolls. The treated paper is oil- and water-repellent.

EXAMPLE 3

This example further illustrates the effectiveness of the process of this invention and variations within the scope of the process. Samples of kier-boiled standard cotton jeans cloth are treated as described above with solutions

65 It will be apparent that the treating solution should contain at least about 1 percent of the treating agent and that at least about 0.2 percent fluorine should be present in the treated fabric after curing to provide desirable oil, water and soil repellency after laundering. However, it is found that a solution containing 0.1 percent can be used to treat fabrics, which then show excellent oil, water and soil repellency before laundering.

EXAMPLE 4

70 N-methyl-5-perfluorooctanesulfonamidoheptadecanoxymethyl pyridinium chloride is prepared as follows, using the general procedure described above. A mixture of 198 parts of the dry sodium salt of N-methyl perfluorooctanesulfonamide and 61.5 parts of 5-chloropentyl acetate is stirred at about 120° to 140° C. for 15 hours and

then cooled. The reaction mixture is extracted with successive portions of diethyl ether, the combined ethereal extracts evaporated and the residue distilled under reduced pressure. N-methyl-5-perfluoroctanesulfonamido-pentyl acetate boils at about 140° C. to 145° C. under 0.4 mm. Hg pressure and melts at about 40° C.

To a solution of 131.3 parts of the acetate ester in about 100 parts of ethanol is slowly added a solution of 15 parts of sodium hydroxide in 40 parts of water. The resulting solution is stirred at about 60° to 70° C. for 15 hours, cooled, and diluted with an equal volume of water. The mixture is acidified with dilute hydrochloric acid and the crystalline 5-(N-methyl-perfluoroctanesulfonamido)pentanol is collected. After drying, it melts at about 73.5° to 75° C.

A mixture of 35 parts of the above N-methyl-5-perfluoroctanesulfonamido-pentanol and 2 parts of paraformaldehyde in about 120 parts of toluene is treated with hydrogen chloride gas as described hereinabove until absorption ceases and the solution has become clear and homogeneous. The toluene is then removed under reduced pressure and the N-methyl-5-perfluoroctanesulfonamido-pentanoxymethyl chloride is obtained as a waxy residue.

The residue is taken up in 100 parts of diethyl ether and 7 parts of pyridine are added. After standing for about 16 hours, the crystalline ether-insoluble N-methyl-5-perfluoroctanesulfonamido-pentanoxymethyl pyridinium chloride formed in the reaction has precipitated and is collected, washed with ether and dried. It is obtained as hard waxy solid melting about 108-120° C.

Calculated for $C_{20}H_{20}F_7SO_3N_2Cl \cdot \frac{1}{2}H_2O$: C=32.6; N=3.81; H_2O =1.22. Found: C=32.6; N=3.8; H_2O =1.8.

N-methyl-5-perfluoroctanesulfonamido-pentanoxymethyl pyridinium chloride is employed for treating kier-boiled cotton jeans cloth as described above, using a 2 percent aqueous solution containing 1 percent of sodium acetate. The soaked cloth is dried for 30 minutes at 100° C. and then cured for 5 minutes at 135° C. The treated fabric has an oil rating of 100+ and a spray rating of 80-; and contains 0.5 percent F. After laundering in the Launder-O-Meter, the oil rating is 100+, spray rating 70+ and there is still 0.48 percent F in the cloth. The dry soil rating both before and after laundering is +3, that is, visually estimated, the treated cloth is less than about one-half as readily soiled as an untreated sample of the cloth.

EXAMPLE 5

When N-ethyl-6-perfluoroctanesulfonamido-hexanol, N-methyl-4-perfluorobutanesulfonamido-butanol, N-perfluoroctanesulfonamidoethanol and N-propyl-2-perfluoroctanesulfonamidoethanol are employed in the above procedures, except that anhydrous hydrogen bromide is used instead of hydrogen chloride, the corresponding bromomethyl ethers are formed as waxy solids, and are respectively, N-ethyl-6-perfluoroctanesulfonamido-hexanoxymethyl bromide, N-methyl-4-perfluorobutanesulfonamido-butanoxy-methyl bromide, N-perfluoroctanesulfonamidoethoxy-methyl bromide and N-propyl-perfluoroctanesulfonamidoethoxy-methyl bromide. When these latter bromomethyl ethers are dissolved in anhydrous ether and the calculated stoichiometric amounts of triethylamine are added, using the procedure hereinabove set forth, the surface-active quaternary salts which precipitate are respectively (N-ethyl-perfluoroctanesulfonamido-hexyloxy-methyl) triethylammonium bromide, (N-methyl-perfluorobutanesulfonamido-butoxymethyl) triethylammonium bromide, (N-perfluoroctanesulfonamidoethoxy) triethyl ammonium bromide and (N-propyl-perfluoroctanesulfonamidoethoxymethyl) triethyl ammonium bromide.

Likewise, using the procedure described in Examples 1 and 4, but starting with N-butyl-8-perfluorododecane-sulfonamido-octanol and N-hexyl-12-perfluorohexanesulfonamido-octanol and

fonamido-dodecanol, there are produced N-butyl-8-perfluorododecane-sulfonamido-octanoxymethyl chloride and N-hexyl-12-perfluorohexanesulfonamido-dodecanoxymethyl chloride, from which are prepared, using tri-n-hexylamine in ether solution, the corresponding N-butyl-8-perfluorododecane-sulfonamido-octanoxymethyl-tri-n-hexylammonium chloride and N-hexyl-12-perfluorohexanesulfonamido-dodecanoxymethyl-tri-n-hexylammonium chloride.

These quaternary compounds are also useful for imparting water- and oil-repellent finishes to textiles as described herein.

What is claimed is:

1. A compound of the formula:

wherein R_f is perfluoroalkyl having 4 to 12 carbon atoms, R is alkylene having 1 to 12 carbon atoms, R' is a member of the group consisting of hydrogen and alkyl having from 1 to 6 carbon atoms, and X is a halogen of the group consisting of chlorine and bromine.

2. A compound of the formula:

wherein R_f is perfluoroalkyl having 4 to 12 carbon atoms, R is alkylene having 1 to 12 carbon atoms, R' is a member of the group consisting of hydrogen and alkyl having from 1 to 6 carbon atoms, Q is a nitrogenous organic residue selected from the group consisting of trialkylamino having up to 36 carbon atoms, alkaryl amino having up to 8 carbon atoms, pyridino, picolino, lutidino and quinolino and X is a halogen of the group consisting of chlorine and bromine.

3. N-methyl-11-perfluoroctanesulfonamido-hendecanoxymethyl chloride.

4. N-methyl-5-perfluoroctanesulfonamido-pentanoxymethyl chloride.

5. N-methyl-11-perfluoroctanesulfonamido-hendecanoxymethyl pyridinium chloride.

6. N-methyl-5-perfluoroctanesulfonamido-pentanoxymethyl pyridinium chloride.

7. The process for the production of halomethyl ethers which comprises treating a compound of the formula:

wherein R_f is a perfluoroalkyl group containing 4 to 12 carbon atoms, R is an alkylene bridging radical containing 1 to 12 carbon atoms and R' is a member of the group consisting of hydrogen and alkyl radicals having from 1 to 6 carbon atoms; with formaldehyde and a member of the group consisting of anhydrous hydrogen chloride and anhydrous hydrogen bromide while maintaining the temperature in the range of from about 25° to 100° C.

8. A cellulosic fabric having oil- and water-repellent properties, finished with N-methyl-11-perfluoroctanesulfonamido-hendecanoxymethyl pyridinium chloride.

9. A cellulosic fabric having oil- and water-repellent properties, finished with N-methyl-5-perfluoroctanesulfonamido-pentanoxymethyl pyridinium chloride.

10. The process for rendering fibrous materials water- and oil-repellent, which comprises treating the fibrous material with a quaternary amine salt of a compound of the formula:

wherein R_f is perfluoroalkyl having 4 to 12 carbon atoms, R is alkylene having 1 to 12 carbon atoms, R' is a member of the group consisting of hydrogen and alkyl having from 1 to 6 carbon atoms, and X is a halogen of the group consisting of chlorine and bromine, in aqueous medium buffered to about pH 5.5 to 6.5, drying the treated fibrous material and heating the dried, treated material to about

100° to 140° C. for a period of the order of 5 to 30 minutes.

11. A fabric finished with a quaternary amine salt of a compound of the formula:

wherein R_f is perfluoroalkyl having 4 to 12 carbon atoms, R is alkylene having 1 to 12 carbon atoms, R' is a member of the group consisting of hydrogen and alkyl having from 1 to 6 carbon atoms, and X is a halogen of the group consisting of chlorine and bromine; whereby the fabric contains residual combined fluorine and has oil- and water-repellent properties.
